UNITED STATES PATENT OFFICE.

WILLIAM MARTIN, OF PHILADELPHIA, PENNSYLVANIA, ASSIGNOR TO
THOMAS DOLAN AND R. WILLIAMS, JR., OF SAME PLACE.

DESIGN FOR STOCKING FABRIC.

Specification forming part of Design No. 7,731, dated September 1, 1874; application filed August 19, 1874.
[Term of Patent 3½ years.]

CASE J.

To all whom it may concern:

Be it known that I, WILLIAM MARTIN, of Philadelphia, Pennsylvania, have invented a Design for Stocking Fabric, (J,) of which the following is a specification:

The figure in the accompanying drawing represents sufficient of a stocking fabric to illustrate my design, the remainder being merely a repetition of that which appears.

The design is composed mainly of parallel stripes A and B, each of which, throughout a portion of its length, is of the peculiar scalloped or zigzag character clearly shown in the drawing, and a peculiar and pleasing effect is produced by arranging the zigzag portions of the several stripes directly opposite each other throughout the pattern.

Each stripe A is composed of three parallel bars, *a*, *b*, and *c*, the edges of which are sharp-

ly defined by narrow ribs *d*, of a shade or color differing from that of the said bars.

The stripes B are simple bands of a uniform shade or color, and the body of the fabric is ornamented by narrow ribs C, of the same scalloped or zigzag character as the stripes.

Irrespective of the colors employed, I claim—

The design for a stocking fabric, consisting of parallel stripes A and B and ribs C, of the scalloped or zigzag character described, and represented by the drawing.

In testimony whereof I have signed my name to this specification in the presence of two subscribing witnesses.

WM. MARTIN.
